UNITED STATES PATENT OFFICE.

THOMAS F. GAYNOR, OF LEXINGTON, KENTUCKY.

RAPID FIRE-SIGNAL.

SPECIFICATION forming part of Letters Patent No. 352,645, dated November 16, 1886.

Application filed April 3, 1886. Serial No. 197,689. (No model.)

To all whom it may concern:

Be it known that I, THOMAS F. GAYNOR, a resident of Lexington, in the county of Fayette and State of Kentucky, have invented 5 certain new and useful Improvements in Rapid Fire-Signals, of which the following is a specification.

This invention relates more particularly to a system of automatic fire-alarms.

10 The following are some of the principal objects of this invention:

First, to enable any person who may discover a fire to give an alarm with the least possible delay to the fire department, or other 15 officials to whom such information may be necessary, without the delay incident to procuring a key from a key-holder or giving notice to a key-holder, as is the case when fire-alarm boxes are used which require to be unlocked before the signal mechanism can be 20 operated; second, to enable the officials to know when a signal is about to be sent, even before it is given, that the person giving such signal may be detained at the box until the 25 fire department reach the box and are informed of the exact location of the fire; third, to detect any person who may give a false alarm of fire; fourth, to enable any person to be at liberty to go to the next signal-box and 30 signal in case the alarm is not received at the central station; fifth, to automatically detain the person giving an alarm in the signal station if his signal has been received; sixth, to leave it to the discretion of the fire department 35 whether such person will be locked in the station or not; seventh, to give a person thus detained the means of calling for his liberation as soon as possible; eighth, to give policemen or authorized persons the means of 40 preventing their being locked in such stations; ninth, to give such policemen or authorized persons the means of using the station for independent signal purposes without giving any preliminary signals to the central office; tenth, 45 to enable such authorized persons to liberate any person within the station; eleventh, to warn the central-office attendant when intruders having no business in the station enter it, even if they do not use the mechanism, of their presence, 50 and if the attendant so chooses he can lock the offending person in the station until detected.

and released; twelfth, to provide for cities a combination telegraph-station that can be used for either or both fire or police purposes, as may be desired, and for all other uses, as will 55 be found convenient with the apparatus hereinafter described, all of which will be fully set forth in the description of the accompanying drawings, making a part of this specification, in which—

Figure 1 is a central vertical section of a booth or patrol-box, showing the door-locking mechanism in place. Fig. 2 is a similar view showing the signal-box in position. Fig. 3 is a section on line xx , Figs. 1 and 2. Fig. 4 is 65 a plan view of the electrical door-lock with one of the plates removed. Fig. 5 is a detail view of the signal mechanism, with a diagram showing its circuit connection with the main office, adapted for closed circuit. Fig. 6 is a 70 detail view and a diagram of the circuit-connection with the main office adapted to work in open circuit.

A represents a booth or compartment in which the signal mechanism is placed. It is 75 provided with a door which must be closed in order to operate the signal mechanism. I have shown this booth of the form and construction of an ordinary policeman's box, but with the door opening into it; but this is mere 80 convenience for illustrating the signal apparatus to be used in said patrol-box.

B represents the central office where the signals are received from the stations, where the battery I is located.

85 I have shown the signaling apparatus preferably employed in detail, as any well-known form may be employed; but I prefer to use the signal-boxes and mechanism set forth in my Letters Patent No. 335,026, dated January 26, 1886.

b represents the signal-box located in the booth in the rear of the door a.

a' represents a connecting-rod hinged to the door at one end, and to a slide, c, which is 95 mounted and slides upon the top of the signal-box b. This slide is provided with an orifice, e, and so connected to the door by the rod a' that when the door is shut the orifice e is vertically opposite an opening made in the top of the signal-box, so that a person can insert his finger through said orifice and reach

the button *d* (shown in Figs. 5 and 6) and trip the fire-alarm mechanism located in said box, to send in signals to the main office.

1 represents a hinged or flexible floor, which is depressed by the weight of a person entering the box to close a circuit, and thereby send an alarm to the main office. To accomplish this automatic sending in of an alarm by the weight of a person in the booth, I have provided the following instrumentalities:

2 represents a connecting-rod attached to the yielding floor 1 at one end, and at the other to a sliding plate, 3.

4 represents a retractile spring for pulling up the rod when the weight is removed from the floor by the person leaving the box.

5 is a retractile spring for bringing the floor 1 back into its normal position. In Fig. 5 I have shown the sliding plate 3 as adapted to operate a signal, D, at the main office.

6 represents the circuit-wheel of an automatic signal apparatus placed within the box *b* in the usual manner; 7, a detent-arm, and 8 a tripping-lever, which are preferably constructed as described in my said former patent. When the rod *d* is pushed down by the button, the detent 8 is depressed, setting the arm 7 in motion for sending in an automatic alarm.

9 represents the stem of the sliding plate 3, extending through the partition 10, which is made to serve as a guide for said stem 9, which terminates directly under the lever 8, so that it cannot be depressed until the floor 1 descends, carrying slide 3 and stem 9 down a sufficient distance to allow the button to move and set the detent-arm 7 free. By this means an alarm cannot be sent in unless the person is in the box and the floor depressed by his weight.

11 represents a gong; 12, a magnet connected in circuit with the signal apparatus, whereby a person is apprised of the working of the circuit at the time of the sending of the alarm.

13 represents a circuit-breaking key, also in the signal-box, for allowing independent signals to be sent over the same line as the fire-alarm or automatic signal.

14 represents a spring terminal pivoted to the sides of the box, one end of which is in side contact with the plate 3.

15 represents an opposite polar terminal, which has a similar spring-connection to the same plate.

16 represents a circuit-closing plate, which is insulated from but attached to the sliding plate 3. When the plate 3 is pulled down by the weight on floor 1, the terminal 14 passes opposite the notch 17 and temporarily breaks the circuit and sends in the first alarm to the central station. When the plate 3 is retracted, the circuit is closed again, the spring 14 yielding to pass over the notch and bring the parts into the relation shown in Fig. 5.

18 represents a pivoted lever carrying lugs 19 and 20, which are provided for the pur-

pose of locking the plate 3 and rod 4 in either position, as may be desired. The lower end of the lever 18 projects forward, forming a finger, 70 21, against which the key 22 strikes and turns, moving the lever upon its pivot and driving, say, the lug 19 into the notch 23. As soon as the key is turned back the retractile spring 25 forces the lever 18 back into the normal position shown in Fig. 5.

It is sometimes desired to hold the plate 3 in its depressed condition to maintain a closed circuit, so as to prevent more than one signal from being sent in until it is released. For 80 this purpose I provide the notch 24, into which the lug 20 automatically engages when the plate 3 is depressed. A key releases it in the same way as before explained for releasing the lug 19, when the plate 3 will be retracted by the 85 spring 4. Thus by means of the lever 18 I am enabled to automatically lock the plate 3, to prevent more than one signal from being sent in until an authorized person has set the same in position for operation. I am also enabled to lock the plate 3 up to prevent, preliminary calls from going in when an authorized person is working in or about the box. For this purpose the key-hole 22 is made through both casings of the call-box, so that 95 this lever 18 can be worked from the outside as well as the inside of the booth. By means of the lever 18, also, a circuit may be established without the moving of the plate 3, by means of the key throwing the tail of the 100 lever in contact with the spring terminals 14 and 15. This portion of the lever is shown insulated from metallic contact with the main portion of the lever.

In order to connect the lock electrically with 105 the signal-circuit, I have provided the following instrumentalities:

26 represents one terminal, 27 another insulated terminal attached to the base of the signal-box.

28 represents a circuit-closer which is insulated from and connected to the sliding plate 3.

To these terminals I connect the wires leading to the lock, which is constructed as follows:

30 represents an electro-magnet secured to 115 the base of the lock-plate.

31 represents an armature, the free end of which serves as a stop for engaging with the bolt 32, which is also pivoted to the base of the 120 lock-plate, serving as a detent to hold the bolt normally open, as shown in full lines in Figs. 4 and 5. As soon as the armature 31 is attracted by the magnet the bolt 32 is released, and the spring 33, Fig. 4, draws it around into 125 the horizontal position shown by dotted lines, where it engages with the catch 35, which is held normally in position by the spring 34.

36 represents a key-hole, into which a key is inserted for engaging with the catch 35, so as 130 to release the bolt 32 and allow it to be set in position, as shown in Fig. 4.

In order that the ground-connection, which is necessary for working the armature 31, may

be broken automatically by the locking-bolt 32, so as not to interfere with the operation of the locks of either station, I have provided the following instrumentalities:

5 37 represents a rod sliding in ears 38, the bottom of which carries the circuit-closer 39, which is automatically retracted by the spring 40. As the bolt 32 rises into the horizontal position it engages with the knob or catch 41, 10 lifts the rod 37, releasing the end 39 from terminal connection with the posts 42 and 43, breaking the circuit connections of the magnet 30.

The lock and signal mechanism are electrically connected to the signal-receiving mechanism at the main stations, which consists of the following devices:

E represents an independent signal office—say a police-station.

20 45 represents a circuit-breaker, 44 a retractile spring for holding the key normally closed.

46 represents a gong, by means of which the signals are given. Any number of such independent signal devices may be connected into 25 circuit for various police and fire circuits, as may be desirable.

B represents the central station, in which is placed an automatic circuit-closer for locking the booth-door, arranged as follows:

30 47 represents an automatic circuit-closing device, which consists of a ratchet and a windlass driven by a weight or spring, 48, carrying a finger, 49, which turns with the ratchet-wheel, which is set in motion by the release of the detent 52, which is operated by the magnet 53, so as to bring the terminal 49 in contact with the terminals 50 and 51, bringing the ground G into connection with the battery I.

The automatic fire-alarm is preferably operated by a metallic circuit, which is represented in Fig. 5 as a closed circuit, which is as follows: By wire J, from the signal D at the main office, through the circuit-breaker 45, thence by wire J to terminal 15 in the signal-box in Fig. 5, thence through the circuit-closer 16, terminal 14, circuit-wheel 6, circuit-breaker K, wire l, battery I. The breaking of this circuit, as shown in diagram, Fig. 5, is for sending in signals by the operation of plate 3 and 50 the circuit-breaker 6 and K, or by the operation of circuit-breakers 45.

It is desirable to have the electrical locking mechanism operated independent of this metallic circuit, and for this purpose I establish 55 two ground-connections, so that by making a ground-circuit the lock may be operated from the central office, as follows:

G represents the ground at the main office; g, the circuit-closer, which is connected by 60 wire g' to the battery I, and thence by wire l to magnet 12, wire L to magnet 30, thence by wire M to polar terminal 26, which is metallically connected to the polar terminal 27 by the descent of slide 3, bringing the circuit-connectors 28 in contact with said terminals 26 27, thence by wire N to ground G'. This circuit 65 works as follows: As soon as the floor 1 is de-

pressed, bringing down slide 3 and establishing the circuit through terminals 26 27, the metallic circuit is broken by carrying the 70 spring terminal 14 into the space 17, thereby sounding the alarm D at the main office, so that the attendant at the main office is notified of the grounding of the magnet in the lock-box by this sending in of the signal, and also of the presence of persons in the box, when by operating the circuit closing key g he electricifies the magnet 30, bringing down the armature 31 and locking the door of the compartment in which this is placed. It is sometimes 80

desirable, however, to have this grounding accomplished automatically by the sending in of the signal through the circuit-breaker K. To accomplish this I have provided automatic ground-closing mechanism 47 48 49 50 51 52 85 53. When the circuit-breaking wheel 6 is started in motion, as the circuit is broken, magnet 53 is operated and the detent 52 is released by the breaking of the circuit, when the spring 54 draws back the detent and the weight 90 moves the ratchet-wheel 47 one step. The closing of the circuit by the tooth of the wheel 6 retracts the detent 52. As soon as the circuit is broken again the ratchet 47 moves one step forward, and this is repeated until the circuit-plate 49 is brought into metallic contact with the posts 50 51, when the ground is established with the lock-box and the magnet 30 is instantly operated, releasing the bolt 32 and locking the door

The circuit device at the central station may be set so as to require any desired number of steps to establish this ground-circuit.

55 55 represents a stop for arresting the motion of the circuit-closer 49 to hold the ground-connection, if desired.

In order to prevent automatic grounding of the magnet 30 in the lock box at the signal-station, the circuit-closer 49 is set a sufficient distance away from the posts 50 51, so that the preliminary signal sent in by the depression of the floor 1 will not operate the lock. The circuit-closer is, however, set near enough to the posts 50 and 51, so that the first or second closure or breaking of the contact of the 115 circuit-wheel with the contact-spring will quickly bring the circuit-closer in contact with the two posts 50 51, thus completing the ground-circuit while passing over the posts, thus operating the locking-bolt through magnet 30 before the person has time to leave the booth after giving the alarm. The contact of the circuit-closer 49 is made with posts 50 51 while passing over the posts during a minute interval of time, and is not a permanent contact, thus leaving no permanent ground-circuit to interfere with the coming in of signals over the metallic circuit, even if an accidental ground-connection of the opposite pole existed anywhere in the circuit.

Fig. 6 illustrates my device adapted to the open-circuit system. In this system the lock and signaling mechanisms at the central office and signal-station are the same as in Fig. 5,

but the circuit connections are changed as follows: The metallic circuit is normally open. 57 represents the circuit-closer insulated upon plate 3. It is provided with a side contact-lug, which strikes a lug on the terminal 58 as the plate 3 is in the act of moving down, but passing beyond said lug to break the circuit. This sends in a cautionary signal, caused by the depression of the floor 1. When plate 3 has been depressed, the lug 20 on lever 18 engages with notch 24, holding it down. It is released by a key, as described for the corresponding mechanism in Fig. 5. Now, if when this plate 3 is depressed the alarm is sent in 15 from the signal station to the central office, and the operator there releases the lock-bolt 32, the ground for this circuit-connection, which is made through circuit-breaker 43 and magnet 30, is cut out by the rising of the lock-bolt.

To secure a ground for independent signaling when the door of the booth is locked, I employ a switch, P, bringing in the ground-wire N', and thus establishing an independent circuit, which can be operated by the circuit-breaking key independent of the automatic signal devices.

The metallic circuit in Fig. 6 is as follows: Through battery I' to magnet 53, thence to 30 the magnet of the signal D, thence by wire J to key 45, thence by wire J to the circuit-wheel 6, thence by wire J to terminal 58, thence by 57 when it is in contact therewith by wire l' to wire L to contact-spring K, thence 35 through magnet 12 and by wire l to battery I'.

The ground of the circuit for locking the bolt 32 and for independent signaling is as follows: Through the ground G at central office, by key g, through magnet 53, battery I, 40 wire l, magnet 12 in the signal-box; thence by wire L to magnet 30, and thence by wire M to terminal 26, connecting-plate 28, terminal 27, and wire N' to ground G'.

When it is desired to send in independent signals by key 45 at the independent station, said key, when operated, grounds wire J through the wire J'. Thus key 45, say, at the police station, may be operated to give signals through magnet 12 without affecting 45 the circuit for sending in automatic signals or the tripping devices of the lock-circuit. Thus I am enabled to maintain two independent circuits in connection with the central and signaling offices, one of which I prefer should be a ground-circuit, which saves the expense of an additional wire; but I do not wish to limit my claims to a metallic and a ground circuit, as either kind may be employed, if desired.

The operation of my device is as follows: When a person wishes to give an alarm of fire, he goes into the booth and closes the door, which is held normally closed by a spring. The weight of the person entering the booth depresses the floor and moves plate 3 to form a circuit-connection, and allows the tripping-detent 7 to be operated by the button d. The

depressing of the floor and setting of plate 3 has sent a cautionary signal to the central station, giving one ring to the bell D, so that the operator at that station is notified that an alarm is about to be sent in, or that a person is in the booth. The automatic alarm through the circuit-breaking wheel 6 is sent in by depressing the button d, the detent 8 allowing the 75 arm 7 to be revolved in the ordinary manner common in fire-signals, which alarm is indicated by the bell D at the central office. The depressing of plate 3 brings the circuit-connecting plate 28 in contact with the terminals 80 26 27, making the circuit-connections, which are operated by battery I, in two ways, either by depressing the key g at the central office and through the ground at the signal-station, or through the magnet 53 of the central station 85 operating the armature 31 and releasing the lock. When it is desired to operate this lock-bolt only by the key 45, the switch R at the central station is turned so as to cut out magnet 53 and the automatic ground-circuit closer operated thereby. If, however, it is desired to have the lock-bolt 32 worked automatically by the sending in of the automatic fire-signal, the switch R is opened, when the current will pass through magnet 53 and operate the detent-armature 52 and move the ratchet-wheel 47 and the circuit-connector 49 forward into contact with the terminals 50 51, thereby automatically establishing the ground-circuit and operating the armature 31 of the 90 lock at the signal station.

When a policeman or authorized person desires to enter the booth or signal-station for independent signaling, he may, by means of a key move lever 18 and lock the connecting-plate 3 up, and then his weight upon the station-floor will not affect the movement of said plate. In this position he may send in independent signals from the circuit-breaker 13; but when the circuit is thus established or 105 broken the automatic signal will not work, as the holding of plate 3 up prevents the detent 7 from being dropped to start the circuit-breaking wheel 6 in motion.

It will be noticed, also, that so long as plate 115 3 is held normally in the position shown in Figs. 5 and 6 there is no ground established through the lock-magnet 30; hence the lock-bolt cannot be automatically tripped or set free.

I have shown and described the circuit closing and breaking mechanism by the term "plate 3," the function of which is to open and close the circuits by connecting and disconnecting the circuit-terminals, which are 125 shown as worked in a ground-circuit; but the use of an additional wire and employing a second metallic circuit for working the magnet in the lock would be the equivalent of the ground-circuit. So, also, any moving circuit 130 making and breaking device in lieu of plate 3 which would connect or disconnect said circuits would be the equivalent of said plate 3. If desired, a gong may be placed on the out-

side of the booth, adapted to be sounded by the person inside to call assistance in case of the neglect of the department to release the person locked therein. The bolt 33 of the 5 lock is turned by a handle of any desired form of construction.

I claim—

1. In a signaling-circuit comprising a central station and a booth or signal-station connected in electric circuit, said booth being provided with a door and a locking mechanism therefor, the combination, with said locking mechanism having a bolt adapted to be electrically tripped and locked, of a circuit-controller located at the central station for operating said bolt, substantially as described. 15

2. In a signaling-circuit comprising a central station having an electric circuit connected with the signal mechanism in a booth or signaling-station provided with a door and a lock, the combination, with said lock, the bolt of which is electrically tripped and locked, of an armature, a magnet, and a circuit making or breaking mechanism at the central office, substantially as specified. 25

3. In combination with the door of a signal-booth, a lock having a bolt held by tripping mechanism and electrically connected with a signaling apparatus in said booth, which is in 30 turn connected in circuit with a central station having both a ground and a metallic circuit, the connections of the former being established at the central station by the operation of the connecting-plate 3, substantially as specified.

4. In a booth having a door, a signal apparatus comprising a push-button, a trip mechanism, and an automatic signal device inclosed in a box and provided with an aperture exposing the push-button for sending signals by releasing the trip mechanism of the signal-box, which aperture is covered by mechanism connected to the door, whereby such aperture is exposed only when the door is closed, substantially as specified. 45

5. In a booth having a door, a signal apparatus comprising a push-button and an automatic signal device inclosed in a box and provided with a tripping device which is covered 50 by mechanism connected to and operated by the booth-door, whereby said tripping mechanism is exposed for operation only when the door is closed, substantially as specified.

6. In combination with the automatic signal device located in a box, b, the tripping mechanism held from operation by the sliding plate 3, which is moved to establish circuit-connections for sending alarms, the foot-board 1, and the rod 2, connected with said plate, substantially as specified. 55

7. A signal device electrically connected with two independent circuits for automatic alarms and independent signaling, respectively, the ground of one circuit being established by terminals which are cut in and out by sliding plate 3, electrically connected to the signaling 60

device and inclosed in a box, b; at a signal-station, substantially as specified.

8. In combination with the automatic signal device located in box b, the sliding plate 3, 70 having ground and circuit terminals for establishing a circuit by the moving plate 3, and a push-button for tripping of the automatic signal device for sending in alarms, substantially as specified. 75

9. In combination with a signal-booth having a door provided with a lock, the automatic signal devices located in a box in said booth, the connecting-plate 3, having ground-connecting terminals connected in circuit with the magnet and bolt-tripping mechanism of the lock, and ground-connections through said lock-magnet for providing a circuit for tripping the bolt independent of the signal-circuit, substantially as specified. 80

10. In combination with the automatic signal devices located in a box, the connecting-plate 3, having ground-connecting terminals connected in circuit with the magnet and bolt-tripping mechanism of the lock in said box, 90 and ground-connections through said lock-magnet to ground at a certain station for providing a circuit for tripping the bolt independent of the signal-circuit, and an automatic ground cut-out operated by the bolt after 95 it is tripped, whereby the ground-circuit may be established at another station for similar signals and operations, substantially as specified.

11. In combination with the booth-door of a signal-station, a lock the bolt of which is automatically tripped by a magnet having one ground-connection at the booth and the other ground at the central station, which are automatically connected in circuit by plate 3 of the signal device, substantially as specified. 100

12. In combination with the lock e, a magnet connected in circuit with the automatic ground-closer and terminals located at the central office, said magnet controlling a bolt-tripping armature and connected in and operated by the automatic signal-circuit, substantially as specified. 110

13. In combination with the automatic signal located in a booth and exposed only when the door is closed, a lock and magnet, a bolt-trip for locking the booth-door, and an automatic ground-closing terminal located in the central office and operated by the automatic signal device in said booth, substantially as specified. 115

14. In combination with the circuit making and breaking plate 3 of the signal device, the yielding floor 1 of the booth connected to said plate, whereby the circuit-connections are 125 made for signaling and locking the door by the weight of a person on the floor 1 of the booth, substantially as specified.

15. In combination with the sliding circuit-closing plate 3, located in the box b, having a 130 circuit-connection with the automatic signal devices, the lock-bolt 18, pivoted in said box

and engaging with said plate 3 and operated by a key inserted into a key-hole in said box, whereby said plate 3 is locked or released, substantially as specified.

- 5 16. In combination with the circuit-closing terminals 26 27 and ground and line wires, the plate 3, having a circuit-connection and means for moving it up or down, as and for the purpose set forth.
- o 17. In combination with plate 3, connected in circuit with the signal mechanism, the circuit-connecting plate 28, insulated from plate 3, terminals 26 27, magnet 30, lock-bolt 32, and switch P, for bringing in ground G' when the ground-connection through magnet 30 is cut out by the lock-bolt, substantially as specified.

18. In combination with the door of a booth and mechanism covering the tripping devices of a signal-box mechanism connected to and operated by said door, the movable plate 3, yielding floor 1, and the circuit closing and breaking rod 2, connected to the yielding floor and to said plate, whereby the signal-circuits are established by a person entering the booth and closing the door, substantially as specified.

In testimony whereof I have hereunto set my hand.

THOMAS F. GAYNOR.
